UNITED STATES PATENT OFFICE.

JOHN M. PALMATIER, OF NEW YORK, N. Y.

LOW-WATER DETECTOR FOR STEAM-BOILERS.

SPECIFICATION forming part of Letters Patent No. 308,979, dated December 9, 1884.

Application filed March 18, 1884. (No model.)

To all whom it may concern:

Be it known that I, JOHN M. PALMATIER, of the city and county of New York, in the State of New York, have invented a new and 5 useful Improvement in Low-Water Detectors for Steam-Boilers, of which the following is a specification.

My invention relates to that class of apparatus in which the breaking of an electric 10 circuit when the water in a boiler falls below the desired level will cause the ringing of a bell or sounding of an alarm located in an office or other place near to or remote from the boiler with which the apparatus is connected.

15 An important object of my invention is to dispense entirely with the use of floats to control the breaking of the electric circuit, and to effect the closing of the circuit by the water in a vessel which communicates with the boiler 20 both above and below the normal water-level therein.

In the accompanying drawings, Figure 1 represents a partly-sectional elevation of my apparatus applied to a boiler, a portion of the 25 boiler only being shown. Fig. 2 is a horizontal section on the dotted line $x-x$ of a vessel which communicates with the boiler above the water-line, and in which closing or breaking of the electric circuit is effected; and Fig. 30 3 is a detail sectional view, hereinafter described.

Similar letters of reference designate corresponding parts in all the figures.

A represents a portion of a boiler of any 35 suitable character, here shown as having an upright side, and which, therefore, may be supposed to be an upright boiler. The boiler is supplied with the usual gage-cocks, $a a' a''$, which may be of any suitable character, and 40 the dotted line b designates the proper and safe water-level which it is desired to maintain.

B designates a closed metallic vessel external to the boiler and having a removable lid 45 or cover, B' , at one, in this case the lower, end.

C designates a pipe, which connects the closed vessel B with the upper part or steam-space of the boiler, and C' designates a second 50 pipe, which connects the lower part of the vessel B with the portion of the boiler A at some considerable distance below the water-line b . In the pipes C C' are cocks or valves

$e' e''$, whereby the passage through them may be controlled, and which may be closed when it 55 is desired to detach the vessel B for any purpose—as, for example, for repair or adjustment, as hereinafter described.

D designates an electric circuit in which is an electric battery, d . In the circuit D is 60 also included a relay-instrument, E, whereby is controlled the operation of a bell or other audible alarm apparatus, F, situated in a local circuit, G, in which is a battery, d'' , of suitable strength. One terminal, $**$, of the electric circuit D is connected with the pipe C', and the other terminal, $**$, is connected with a conductor, which extends downward into the vessel B. As here represented, this conductor consists of a light cylindric shell or tube, 70 e , of copper, having two upwardly-projecting stems, $e' e''$, with the latter of which the terminal $**$ is connected.

In order to prevent any electrical communication directly between the vessel B and the 75 conductor e , I form slight indentations or grooves e^* in its exterior, extending vertically from end to end, and in these indentations I cement or otherwise secure a suitable number of small glass rods, f , which come between the inner wall of the vessel B and the cylindric shell or conductor e and prevent contact between them.

The cylindric conductor e may be insulated from the vessel B, by any of the well-known 85 means employed for such purposes, the glass rods f being used simply to illustrate one form of such insulation.

The two rods or stems $e' e''$ pass upward through the closed top of the vessel B and are 90 insulated perfectly therefrom, as best shown in Fig. 3.

The upper portions of the rods or stems $e' e''$ are preferably screw-threaded, and pass through plugs or sleeves g of insulating material snugly fitted in the top of the vessel. To the rods or stems $e' e''$, above and below the said top of the vessel, are applied insulating packing-washers g' and nuts g^2 .

By adjusting the nuts g^2 the rods or stems 100 $e' e''$, and their attached conductor e , may be raised or lowered, as may be desired, for different situations and circumstances, and after adjustment the nuts will be tightened to hold the rods or stems firmly and to compress the 105 packing-washers g' , so as to prevent leakage.

The rods or stems $e' e^2$, where passing through the top of the vessel, may be adjustably secured, insulated, and packed, to prevent leakage, by any suitable or well-known means or devices, 5 the plugs, washers, and nuts $g' g^2$ serving as a sufficient illustration of such means.

When the water-level is at b in the boiler, the level of water in the closed vessel B will be nearly or quite the same, and when the 10 conductor e is in the position shown in Fig. 1 it will be immersed to a considerable depth in the water, and the circuit D will be closed through the pipe C', the water in the vessel B, the conductor e , and rod or stem e^2 , and 15 consequently the bell or alarm apparatus F will not sound. When, however, the water in the boiler drops materially below the level b , or to a point which renders the depth of the immersion of the conductor e insufficient to 20 maintain a closed circuit, the circuit D will be broken and the relay-instrument E will cause the sounding of the bell or audible alarm, which will continue until the water-level is raised sufficiently to close the circuit D.

25 It will be seen that my apparatus is very much more certain and reliable in its operation than apparatus controlled by a buoyant float, and hence by its use gives a measure of safety not realized with the use of an apparatus wherein a float is employed.

I am aware that it is not new to employ, in connection with a closed vessel connected with the water-space and steam-space of a steam-boiler, a float which rises and falls with the 35 level of water in said vessel, and serves through suitable levers or other connections to close an electric circuit and sound an alarm when there is low water in the boiler and a correspondingly low level in said vessel. I do not 40 desire to include such a combination of parts in my invention; and an important object of my invention is to dispense with the use of floats for indicating a low condition of water.

I am also aware that it is not new to employ, 45 in connection with a closed vessel connected with the steam and water spaces of a steam-boiler, an expansion-tube which is arranged horizontally in said vessel, and which will be elongated sufficiently to close an electric circuit when the water in said boiler and vessel falls so low that the tube is exposed to steam. I do not desire to cover by my claims any expansion-tube like that above described.

In my combinations of parts I depend on 55 no float, which is uncertain of action, nor do I depend on any device which must become highly heated by steam after the water becomes low in order to become operative, and which requires nice adjustment of parts. One 60 terminal of my electric circuit is connected with the vessel. The other terminal is connected with a conductor extending into the closed vessel. So long as the level of water in the boiler and vessel is normal the circuit 65 remains closed through the water, which is in contact with the vessel and with the conductor within the vessel. When the water

falls so low that its contact with the conductor is no longer sufficient to close the circuit, the latter is broken and an alarm is sounded. 70 The making or breaking of the circuit is effected directly without the intervention of a float or thermostatic tube.

What I claim as my invention, and desire to secure by Letters Patent, is— 75

1. The combination, with a steam-boiler and a closed vessel communicating with the steam and water spaces of the boiler, of an electric conductor extending within said vessel and insulated therefrom, an electric circuit having its terminals connected one with the said conductor and the other with said vessel, whereby the rise and fall of water in said vessel is made to directly close and break the electric circuit, and an alarm apparatus 85 controlled by the breaking of said circuit by reason of the level of water falling relatively to the conductor in said vessel, substantially as herein described.

2. The combination, with a closed vessel 90 connected with the steam and water spaces of a steam-boiler, of an electric conductor extending within and insulated from said vessel, and capable of adjustment to vary its downward projection into said vessel, an electric circuit having its terminals connected one with said conductor and the other with said vessel, whereby the rise and fall of water in said vessel is made to directly close and break the electric circuit, and an alarm apparatus 100 controlled by the breaking of said circuit by reason of the level of water falling relatively to the conductor in said vessel, substantially 95 as herein described.

3. The combination, with a steam-boiler 105 and a closed vessel communicating with the steam and water spaces of the boiler, of a conductor extending into said vessel and insulated therefrom, an electric circuit containing a battery and a relay and having its terminals 110 connected one with said vessel and the other with said insulated conductor, whereby the circuit will be closed and broken directly by the water rising and falling relatively to the conductor in said closed vessel, and a second 115 electric circuit controlled by said relay and containing an audible alarm apparatus, substantially as herein described.

4. The combination, with a closed vessel, 120 B, of a pipe, C, extending from its upper portion, and to be connected with the steam-space of a steam-boiler, a pipe, C', extending from its lower portion and to be connected with the water-space of the boiler, a conductor, e , consisting of a metallic cylinder or shell arranged within and out of electric contact with the said vessel, and a rod, e^2 , extending upward from said conductor e through the top of the vessel and insulated from the vessel, substantially as and for the purpose herein 125 described.
